(57) **CLAIM**

The ornamental design for a security device, as shown and described.

DESCRIPTION

FIG. 1 shows a perspective view of an embodiment of the new design for a security device, the security device including a lock portion and a U-shaped portion.

FIG. 2 shows a front elevational view of the security device.

FIG. 3 shows a rear elevational view of the security device.

FIG. 4 shows a right side elevational view of the security device.

FIG. 5 shows a top view of the security device.

FIG. 6 shows a bottom view of the security device.

FIG. 7 shows a perspective view of another embodiment of the new design for a security device, wherein the U-shaped portion is optional.

FIG. 8 shows a front elevational view of the security device, wherein the U-shaped portion is optional.

FIG. 9 shows a rear elevational view of the security device, wherein the U-shaped portion is optional.

FIG. 10 shows a right side elevational view of the security device, wherein the U-shaped portion is optional; and,

FIG. 11 shows a bottom view of the security device, wherein the U-shaped portion is optional.

A left side elevational view of the security device is a mirror image of the right side elevational view of the security device.
